H. W. KARN

ARTIFICIAL LIMB

Filed Jan. 7, 1925

Patented Nov. 20, 1928.

1,692,552

UNITED STATES PATENT OFFICE.

HARRY W. KARN, OF PITTSBURGH, PENNSYLVANIA.

ARTIFICIAL LIMB.

Application filed January 7, 1925. Serial No. 997.

My invention refers to improvements in artificial limbs, more especially an artificial articulated leg, consisting of an upper thigh portion adapted to form a receiving connecting receptacle for the stump of the human limb, and having a lower portion pivotally connected to swing at the knee joint.

The improvement consists in providing between the upper and lower articulated sections, flexible tension exerting members adapted to be operated by the user and exerting a swinging action on the lower section, constructed and operating in the manner hereinafter described.

The present improvement is in the same general class of artificial limbs disclosed in my prior Patent No. 1,258,908 of March 12, 1918.

Referring to the drawings, showing one preferred embodiment of the invention,

Fig. 1 is a general view in elevation, showing the device as applied to the body of the user;

Fig. 2 is an enlarged vertical sectional view showing the compound leg member detached from the body and with its lower or shin member relaxed;

Fig. 3 is a partial view in front elevation, showing the knee joint;

Fig. 4 is a similar view from the rear.

The artificial leg members A—B are of generally usual construction, made of wood, or other suitable light strong material, both members being hollow. The upper or thigh member A is provided at its upper portion with a receiving terminal cavity *a* adapted to fit closely around the stump of the amputated limb, and to be held thereon by the tension of the supporting and connecting elements hereinafter described.

The lower or shin member B is pivotally connected by bolt 2 with the upper member A, in the usual manner, whereby the two members are articulated to provide the hinged knee joint, in a manner commonly practiced in this art. The lower outer front portion of the upper member A is rounded, as indicated at 3, and fits neatly within the upper front tapering edge portion 4 of the member B, providing for a small overlapping extension of the members in varying positions.

In addition to the hinged connection by bolts 2, the two members are braced in the rear thereof by flexible connections 5 of rawhide or other suitable material, disposed at

each side of the vertical center, as in Fig. 4, connected at opposite ends by cross bolts or pins 6—7, respectively, and passing through suitable clearance grooves in the upper member. Such connections 5 easily flex on backward swinging of lower member B, as in Fig. 2, but brace said member against forward swinging beyond a normal longitudinal extension, so as to prevent buckling at the knee joint or flexibility other than in a backward direction. Incidentally, the object in view is to permit easy reverse swinging and to prevent undue forward swinging, under the tension exerting power of the operating straps. Such forward swinging is effected through a pair of tension straps or connections 8—8.

As shown, these extend upwardly beyond the top of upper member A to a point where they are connected by loops or other suitable terminals 9 with the hooks or other connections 10 of the suspender straps 11. Said straps, as shown, pass around from front to back over the shoulders of the wearer, as in Fig. 1, and are connected with the terminals 8 of the members 8 at front and back under proper tension, such tension being easily regulated by buckles 12.

Extending across the middle body portion of lower member B is a pin or bolt 13, which constitutes the power transmitting element, whereby to utilize the tension exerting effect of members 8. Such bolt 13, as shown, is located at a sufficient distance below pivotal bolt 2 to ensure good leverage and for the purpose of providing an ample cylindrical bearing for members 8, which may be of rawhide in strap form or of other suitable material, a spool or thimble bushing 14 is used. Said bushing, which may conveniently be of fibre or other similar material, is rotatably mounted around the bolt 13 between the sides of the hollow limb, extending across through its hollow portion, providing for ample bearing surface of the pair of straps with ease and free rotation on the bolt.

A similar bushing or cylindrical bearing 15 is preferably mounted on pivotal bolt 2, providing a rotatable bearing for the rear portions 8^a of the strap members. If desired, however, the bolt 2 may be left bare, but the bushing 15 is of advantage in reducing friction. Said members pass outwardly through inclined front and back openings 16—17 respectively, in the upper member A, such openings being sufficiently above the rounded knee portion to avoid any unnecessary interference

or friction. The member 8—8^a is preferably passed through suitable guiding loops or eyes 18 at the upper front and back portion of member A, so as to maintain it in normal position for easy and convenient connection with the terminals of the suspender supports 11.

It will be understood that the two main members of the limb are properly constructed 10 for easy and smooth interfitting hinge action, ventilation of the interior, and cushioning to prevent shocks or jars, wherever desirable, and with proper clearance openings for access to the interior where necessary.

15 In using the device as constructed and above described, it is placed in firm attaching connection on the stump, the connections are made with the shoulder straps, and proper tension provided. In use, the desired swinging 20 tension is exerted by shoulder action of the wearer, together with proper swinging manipulation, to effect upward pulling of the front or back straps 8 or 8^a in walking. Upon lifting the foot, such upward tension on the 25 front straps tends to exert a forward pulling action on bolt 13, the rear member 8^a being correspondingly relaxed so that the lower member B will then easily and freely swing forward to the desired extent before lowering 30 to the ground. Likewise, upward pulling action on the rear straps, with relaxation on the front straps, will effect the same tension and forward swinging of the shin member.

The operation is easily accomplished with 35 small effort, the parts involved are comparatively few, and simple in construction, and the device is extremely strong and durable and capable of producing a comparatively natural action, after short practice.

40 It will be understood that the device may be variously changed in proportions, construction of the detail parts, varied as to the material used, or otherwise, by the skilled mechanic, but that all such changes are to be included as within the scope of the following claims.

I claim:

1. An artificial limb of the class described comprising a thigh member, a lower leg member, a connecting knee joint pivot, inwardly extending pivot bearings on the thigh member, a roller on the pivot between said bearings, a cross bearing on the lower shin member below the pivot, and a continuous tension member extending inwardly through the front of the thigh member and passing over

beyond the pivot roller and around said cross bearing, then again over the knee joint roller and outwardly through the back of the thigh member, and having terminal connecting devices at its upper front and back ends. 60

2. An artificial limb of the class described comprising a thigh member, a lower shin member, a connecting knee joint pivot, inwardly extending pivot bearings on the thigh member, a roller on the pivot between said bearings, a continuous cross roller bearing on the lower shin member below the pivot, and a continuous tension member extending inwardly through the thigh member at front 70 and back, over and in front of the pivot, and around said roller bearing. 65

3. An artificial limb of the class described comprising a thigh member having inwardly extending pivot bearings, a lower shin member, a connecting knee joint pivot mounted in said inwardly extending bearings with intervening clearance and provided with a middle continuous cross roller in said clearance, a cross bar in the lower shin member 80 below the pivot having a thimble bushing, and a continuous tension member extending inwardly through the thigh member at front and back over and in front of the pivot bearing and around the thimble bushing for exerting leverage action on the lower member, said tension member extending upwardly at front and back and having connection with a shoulder strap. 85

4. The combination with a hollow thigh member having inwardly extending centrally spaced pivot bearings, and a hollow lower shin member pivoted thereto and provided with a cross bearing roller below the pivot, said pivot consisting of a cross pin extending 90 through the inwardly disposed bearings with an intervening roller thereon, of a pair of continuous substantially parallel tension members passing down directly in front and oppositely back of the thigh member, then inwardly at front and back above the joint, over and in front of the pivotal connection and over the bearing roller thereon between the pivot bearings of the thigh member and around the cross bearing roller of the shin 100 member, and having separable connections at their upper outer ends at front and back with a pair of shoulder straps. 105

In testimony whereof I hereunto affix my signature.

HARRY W. KARN.
